UNITED STATES PATENT OFFICE.

RALPH P. TUTTLE, OF ARROCHAR, NEW YORK, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,086,957.

Specification of Letters Patent. Patented Feb. 10, 1914.

Application filed June 28, 1913. Serial No. 775,853.

To all whom it may concern:

Be it known that I, RALPH P. TUTTLE, a citizen of the United States, residing at Arrochar, Staten Island, in the county of Richmond and State of New York, have invented certain new and useful Improvements in Railway-Traffic-Controlling Apparatus, of which the following is a specification.

10 My invention relates to apparatus for controlling railway cars or trains or for giving a signal aboard a car or train.

I will describe one form of apparatus embodying my invention, and will then point 15 out the novel features thereof in claims.

In the accompanying drawings, Figure 1 is a view showing in transverse section a portion of a railway car or vehicle having applied thereto one form of apparatus embodying my invention. Fig. 2 is a view showing in side elevation the apparatus shown in Fig. 1. Fig. 3 is a view showing in perspective a portion of the apparatus shown in Figs. 1 and 2. Fig. 4 is a diagrammatic 20 view showing one arrangement of trackway circuits which may be employed in connection with the apparatus shown in the preceding views. Fig. 5 is a view showing a modification of the apparatus shown in 25 Fig. 1.

Similar reference characters refer to similar parts in each of the views.

Referring first to Figs. 1 and 2, the numerals 1, 1 designate the track rails of a 30 railway along which a car or train, represented by wheels and axle 2, is adapted to travel. Mounted alongside the trackway is a trip 3, the ends of which, as here shown, are inclined. Mounted on the car 2 is a shoe 35 5 adapted to at all times engage the trip 3 and to be raised by one inclined surface or the other of the trip according to the direction in which the car is moving. As here shown, the shoe 5 is suspended by two links 40 16 and 17 pivotally mounted on beams 7, 7 respectively on the car. The shoe 5 is provided at substantially its middle point with a slot 18 in which is pinned the lower end of a rod 9 which extends upwardly through 45 suitable holes in a bracket 8 fixed on a beam 10. The rod 9 and shoe 5 are biased downwardly to the lowest point of their stroke by gravity and by a spring 12 the upper end of which abuts against the upper arm 50 of bracket 8 and the lower end of which

abuts against a collar 19 fixed to rod 9. The spring 12 is constantly under compression, so that the shoe 5 is held down with considerable force; the downward movement of the shoe is limited by the engagement of the 60 collar 19 with the lower arm of bracket 8.

Mounted on the car in suitable bearings 21, 23, 22 and 31, are two transverse shafts 15 and 30. The outer end of shaft 15 is operatively connected with the rod 9 by a 65 crank 14. As here shown, this crank 14 is clamped to a square portion of shaft 15 and is provided with a slot 28 which fits over a reduced portion of the rod 9. It will be seen, therefore, that when the shoe 5 is 70 raised by a trip 3, the shaft 15 will be oscillated through a small arc of a circle.

The two shafts 15 and 30 are coaxially mounted and terminate at their adjacent ends in two enlarged portions 24 and 25, respectively, which form two members of an electro-magnetic clutch device C by means of which the shafts may at times be locked together so that when either shaft is oscillated the other shaft is oscillated also. The 80 clutch C is provided with a winding having two sections 26 and 27.

The two bearings 21 and 22 are extended and so shaped as to form guides for two longitudinally movable plates 32 and 33. 85 (See Fig. 3 as well as preceding views.) These plates rest on a surface 21^a formed integral with the guide 21, and are held from rising from this surface by two fingers 22^a and 22^b formed integral with guide 22. One 90 end of plate 32 is provided with a hole 32^a through which passes freely a pin 34 fixed in the top of clutch member 25, and the adjacent end of plate 33 is provided with a similar hole 33^a through which passes freely 95 a pin 35 fixed in the clutch member 24. Hence, it will be seen that when either or both of the shafts 15 or 30 are oscillated, either one of both of the plates 32 or 33 will be reciprocated in their guides. 100

Plate 32 is biased to the position in which it is shown by a spring 12^a similar to the spring 12. Spring 12^a acts upon a bracket 8^a and upon a collar 19^a fixed to a rod 9^a, which rod is connected with shaft 30 by a 105 crank 14^a similar to crank 14.

Plate 32 is adapted to have longitudinal movement only, but plate 33 is adapted to have both longitudinal and lateral movements. To provide for the lateral move- 110

ment of plate 33, these plates are constructed as follows: Plate 33 is provided, in its edge which lies adjacent plate 32, with a recess 36 having inclined faces, and plate 32 5 is provided with a projection 37 the contour of which matches that of recess 36. Hence, when the two plates are reciprocated simultaneously, plate 33 will not be moved laterally, but when either plate is moved longitudinally with relation to the other the projection 37 will engage one face or the other of recess 36 and cause lateral movement of plate 33 outwardly from plate 32. Plate 33 is biased to position parallel with 15 and in engagement with plate 32 by springs 38 and 39 mounted on a suitable support 40 and bearing on the plate 33. The support 40 is mounted on the surface 21. Plate 33 is the only one of the two plates which is 20 operatively connected at all times with shaft 15, and this plate is reciprocated with each movement of shoe 5. Plate 32 is operatively connected with shaft 15 only when clutch C is energized. As will hereinafter appear, 25 however, both plates 32 and 33 may be provided with mechanical connections by which they are moved by exterior means at different times, if desired.

In the form of apparatus shown in Figs. 30 1 to 3, the clutch C when energized, acts as a means for locking shafts 15 and 30 together so that both plates 32 and 33 are reciprocated simultaneously by shoe 5. When clutch C is de-energized, only plate 33 is 35 moved when shoe 5 is moved.

I do not wish to limit myself to the particular form of electromagnetic clutch shown in the drawings; any other suitable electrically controlled device for locking the 40 shafts 15 and 30 together may be employed.

The lateral movement of plate 33 may be employed to govern the vehicle in any desired manner, such as by giving a signal aboard the vehicle or by causing the progress of the vehicle to be retarded, or both. 45 As here shown, this lateral movement governs the vehicle by causing application of the fluid pressure brakes. A valve device 52 is provided with a stem 41 so located as to 50 be pressed inwardly by the plate 33 when the latter is moved laterally. The valve device 52 may be employed to open the brake pipe or to cause a brake application in any other desired manner. This valve 55 device is preferably so designed that when opened it will remain open until the car is brought to a stop; several forms of valve device of this type are well known in the art.

The electromagnetic clutch C may be controlled from an outside source by any suitable means. As here shown, current is supplied to the windings of this clutch by a contact rail 4 located in the trackway adjacent the trip 3, which rail is engaged by a con-

tact shoe 6 carried by the car. The contact shoe 6 is mounted on a rod 11 which reciprocates vertically in holes in the bracket 8. The shoe and rod are biased to the lowest position of their stroke by a spring 13 one end of which abuts against the upper arm 70 of bracket 8 and the other end of which abuts against a collar 20 fixed on rod 11. For convenience of illustration, I have in the drawing shown the shoe 6 in the raised position, that is, in the position which it occupies while riding on rail 4. The downward movement of the shoe 6 is limited by the engagement of collar 20 with the lower arm of bracket 8; or by the engagement of a nut 41 screwed on rod 11 with the upper arm 80 of bracket 8. As here shown, the contact shoe 6 is electrically connected with rod 9 by a wire 42, rod 9 is electrically connected with crank 14 by a wire 46, (see Fig. 2), one terminal of clutch winding 27 is 85 connected with shaft 15 by a wire 43, the two clutch windings 26 and 27 are connected by a wire 44, and clutch winding 26 is connected with axle 2 by a wire 45. The beams 10 and 10^a are of insulating material, 90 as is also the beam 51 on which bearings 21 and 22 are mounted. Valve device 41 is also insulated from the brake system. Hence, it will be seen that the circuit for clutch windings 27 and 26 is insulated from the car 95 body.

Referring now to Fig. 4, I have here shown one method of applying the apparatus shown in Fig. 1 to one form of signaling system.

In Fig. 4 I have shown a stretch of rail-way track divided by insulated rail joints into a plurality of successive block sections A, B, C, D, E, etc. Traffic through block section E, is governed by a signal S^E, adapted to indicate danger, caution and clear; as here shown, this signal comprises a home arm 47 and a distant arm 48, although it is understood that these indications may be given by other forms of signals. Traffic through block sections D, C, and B, is governed by similar signals S^D, S^C, and S^B, respectively. In the form of signaling system here shown, when a car or train occupies one block section, the signal for that block section indicates danger, the signal for the preceding block section also indicates danger, and the signal for the second block section in the rear indicates caution. I have omitted from the drawing the means for the control of these signals for the reason that such means are well known and form no part of my invention and would unnecessarily complicate the drawing if shown. Located adjacent each signal is a trip 3 each of which may be similar to the trip 3 shown in Fig. 1. Also located adjacent each signal is a contact rail 4 each of which may be similar to contact rail

4 shown in Fig. 1. Each contact rail 4 is provided with a circuit including a battery 50 and a contact 49 operated by the adjacent home arm 47. When the home arm 47 is in the danger or horizontal position, the contact 49 operated thereby is open, but when the home arm 47 is in the clear or inclined position the contact 49 operated thereby is closed. In the drawing I have shown a car 10 or train 2 in block section E, consequently, signals S^E and S^D indicate danger, and since block sections C and B are unoccupied, signal S^C indicates caution, and signal S^B indicates clear. I have also shown a following 15 train 2^a in block section A. It is understood the cars or trains 2 and 2^a are equipped with apparatus similar to that shown in Figs. 1, 2 and 3, but for convenience of illustration the only parts of 20 this apparatus which I have shown in these views are the shoes 5 and 6.

The operation of the apparatus shown in Fig. 4 is as follows: As car or train 2^a enters block section B, the electromagnetic clutch 25 C on this car or train will be energized because contact rail 4 at the entrance end of block section B is energized. Consequently, the valve device 52 on this car or train will not be opened. Similarly, as car or train 30 2^a enters block section C, the valve device 52 will not be opened because contact rail 4 at the entrance end of this block section is energized. If, however, car or train 2^a attempts to enter block section D while block 35 section E is still occupied by car or train 2, the valve device 52 on car or train 2^a will be opened because contact rail 4 at the entrance end of block section D is not energized; car or train 2^a will therefore be brought to a 40 stop shortly after it enters block section D. After having been stopped, if the car or train 2^a is again started and attempts to enter block section E while this section is still occupied by car or train 2, the car or train 45 2^a will again be brought to a stop shortly after entering block section E because contact rail 4 at the entrance end of this block section is not energized.

When apparatus embodying my invention 50 is applied to a railway comprising a single track over which traffic moves in both directions, it is usual to provide a series of steps 3 and contact rails 4 on one side of the track for governing traffic in one direction, and 55 another series of steps 3 and contact rails 4 on the other side of the track for governing traffic in the opposite direction. When so, the form of apparatus shown in Fig. 5 and embodying my invention may be employed 60 to avoid the necessity of turning a car around each time its direction of movement is reversed. In Fig. 5 I have shown a shoe 5 and a shoe 6 on each side of the car, the shoes 5 and 6 and the other apparatus on

each side of the car being the same as the 65 apparatus shown on one side of the car only in Fig. 1. In Fig. 5 I have designated the parts of the apparatus on one side of the car by numerals with exponents as in Fig. 1, and the similar parts of the apparatus on 70 the other side of the car by the same reference characters with the exponent a .

In Fig. 5, the shoe 5^a and rod 9^a are operatively connected with shaft 30, so that when this shoe is raised by a trip 2^a it moves 75 plate 32; and upon such movement the valve device 52 will be operated if clutch C is de-energized or will not be operated if the clutch is energized. It will be seen, therefore, that the operation of the apparatus 80 shown in Fig. 5 is the same as that shown in Fig. 1.

It is understood that when the apparatus shown in Fig. 5 is used, contact rails 4 and 4^a, and trips 3 and 3^a are not located directly 85 opposite each other, because this arrangement would provide mechanical energy for simultaneously moving plates 32 and 33 thereby preventing a brake application even if there were no current in contact rail 4 or 90 4^a. It is also understood that the control of the contact rails 4, 4^a is such that the rails which govern traffic in one direction are constantly energized when traffic is established 95 in the reverse direction, so that no brake applications are caused by the contact rails which govern traffic in the direction opposite to that in which a car or train is moving.

Although I have herein shown and described only certain forms of apparatus embodying my invention, it is understood that various changes and modifications may be made therein within the scope of the appended claims without departing from the spirit and scope of my invention.

Having thus described my invention, what I claim is:

1. In combination, a railway track, a vehicle adapted to travel thereon, a trip in the trackway, two movable members on the vehicle, means on the vehicle operated by the trip for moving one of said members, means on the vehicle for causing simultaneous movement of said members when the one member is moved by the trip or for permitting movement of the one member relative to the other member, and vehicle-governing means operated by said independent movement of the one member relative to the other.

2. In combination, a railway track, a vehicle adapted to travel thereon, a trip in the trackway, two movable members on the vehicle, means on the vehicle operated by the trip for moving one of said members, an electromagnetic clutch for causing simultaneous movement of said members when the clutch is energized and for permitting movement of one member relative to the other.

when the clutch is deenergized, means on the vehicle operated by said movement of one member relative to the other for governing the vehicle, and means for controlling said clutch.

3. In combination, a railway track, a vehicle adapted to travel thereon, a trip in the trackway, two movable members on the vehicle, means on the vehicle operated by the trip for moving one of said members, an electromagnetic clutch for causing simultaneous movement of said members when the clutch is energized and for permitting movement of one member relative to the other when the clutch is deenergized, a contact rail in the trackway adjacent the trip, a contact shoe on the vehicle adapted to make electrical contact with said contact rail, a circuit for the clutch including said contact rail and contact shoe, means for controlling said circuit, and vehicle-governing means operated by movement of one of said members relative to the other.

4. In combination, a railway track, a vehicle adapted to travel thereon, two trips located in the trackway in different longitudinal lines, two movable members on the vehicle, means on the vehicle operated by one of said trips for moving one member, means on the vehicle operated by the other trip for moving the other member, means on the vehicle for causing simultaneous movement of both members when either member is moved by its trips and for permitting movement of either member relative to the other, and vehicle-governing means operated by movement of either member relative to the other.

5. In combination, a railway track, a vehicle adapted to travel thereon, a trip in

the trackway, two movable members on the vehicle, means on the vehicle operated by the trip for moving one of said members longitudinally, an inclined face on each member which faces co-act so that when one of said members moves longitudinally relatively to the other, one member is also moved laterally relatively to the other, means on the vehicle for locking said members together to cause simultaneous longitudinal movement of said members when one member is moved by the trip and for unlocking said members to permit longitudinal movement of one member relative to the other, and vehicle-governing means controlled by said lateral movement of one member.

6. In combination, a railway track, a vehicle adapted to travel thereon, a trip in the trackway, two movable members in the vehicle, means on the vehicle operated by the trip for moving one of said members longitudinally, means comprised in said members for causing lateral movement of one member when one member moves longitudinally relatively to the other, means on the vehicle for locking said members together to cause simultaneous longitudinal movement of said members when one member is moved by the trip and for unlocking said members to permit longitudinal movement of one member relative to the other, and vehicle-governing means controlled by said lateral movement of one member.

In testimony whereof I affix my signature in presence of two witnesses.
